AUTOMATIC FARM GATE

George F. Gump, Walla Walla, Wash.

Application October 31, 1949, Serial No. 124,653

4 Claims. (Cl. 39—29)

1

This invention relates to a gate, and more particularly to a gate that is actuated by a vehicle.

The object of the invention is to provide a gate construction which is adapted to be operated by the movement of a vehicle, such as an automobile, whereby the gate can be opened and closed without the necessity of having an occupant of the vehicle alight therefrom.

Another object of the invention is to provide a gate which has connected thereto a mechanism for automatically opening and closing the gate so that a vehicle can pass along a road that is normally closed by the gate without requiring the vehicle occupant to alight from the vehicle, there being a means for maintaining the gate locked in its opened and closed positions so as to prevent accidental swinging movement thereof.

Another object of the invention is to provide a gate construction which is extremely simple and inexpensive to manufacture.

Other objects and advantages will be apparent during the course of the following description.

In the accompanying drawings forming a part of this application, and in which like numerals are used to designate like parts throughout the same:

Figure 1 is a top plan view of the pair of coacting gates and their operating mechanism, the gates being in closed position;

Figure 2 is a view similar to Figure 1, but with the gates in their opened position;

Figure 3 is a fragmentary side elevational view with the parts in the position of Figure 1;

Figure 4 is a fragmentary side elevational view, but with the parts in the position of Figure 2;

Figure 5 is an enlarged fragmentary front elevational view of the gates, with parts broken away and in section, showing the mechanism for locking the gates in their closed position;

Figure 6 is an enlarged fragmentary horizontal sectional view taken through the gates, the gates being in closed position;

Figure 7 is an enlarged elevational view showing the lock for maintaining the gates in their closed position;

Figure 8 is an enlarged fragmentary elevational view showing one of the combined stop posts and locks for maintaining the gates in their open position;

Figures 9 and 10 are schematic views illustrating the movement of the cables and V-shaped body member.

Referring in detail to the drawings, there is shown a pair of spaced parallel, vertically-dis-

2

posed standards 20 each of which has its lower end embedded in the ground. A gate 21 is pivotally supported by each of the standards 20, and the pair of gates 21 are mounted for opening and closing movements or swinging movements about a vertical axis.

Each of the gates 21 has the same construction, and each comprises or includes a vertically-disposed, hollow, tubular portion 22 and a second vertically-disposed portion 23. For pivotally supporting the gates 21, a plurality of eye bolts 24 rotatably receive the vertical portions 23, and suitable nuts 25 are arranged in threaded engagement with the ends of the bolts 24 so as to maintain the parts in assembled relation. Each of the gates 21 further includes a lower, horizontally-disposed portion 26 which extends between the vertical portions 22 and 23 and is secured thereto for a purpose to be later described.

Slidably arranged in the lower end of each of the vertical portions 22 of the gates 21 is a plunger or trigger 27. A coil spring 28 normally urges the plunger 27 toward its outermost position. For retracting or withdrawing the plunger 27 into the hollow portion 22, a pair of cables 30 and 31 each have one end connected to the upper end of the plunger 27, the cables 30 and 31 being trained over a pulley 29 that is rotatably mounted in the vertical portion 22. The cables or cords 30 and 31 slidably project through a guide ring 32 that is secured to the upper surface of the horizontal portion 26, and the ends of the cables 30 and 31 are arranged in engagement with the free ends of a V-shaped body member 33. A suitable securing element, such as the bolt-and-nut assembly 34, serves to connect the V-shaped body member 33 to the horizontally-disposed portion 26 of the gate 21. It is to be noted that each of the gates 21 has one of the V-shaped body members 33 connected thereto.

The other end of the cable 31 is connected to one end of a coil spring 35, while the other end of the coil spring 35 is connected to a pin 36 which is secured to a shift rod 37. Similarly, the other cable or cord 30 is connected to a coil spring 35 which in turn is arranged in engagement with a pin 36 that is also secured to the shift rod 37. It will be seen that there are a pair of the shift rods 37, the shift rods 37 being arranged in spaced parallel relation with respect to each other lying in a horizontal plane. Each of the shift rods 37 is slidably arranged in suitable bearing members

38 and 39 which remain immobile while the rods 37 are shifted therethrough.

For causing movement of the shift rods 37, a pair of trip bars 40 and 41 are provided, the trip bars 40 and 41 arranged in spaced parallel relation with respect to each other.

Projecting from the trip bar 40 and secured thereto is a pair of plates 42 and 43 which are adapted to be engaged, one at a time, by the wheels of a vehicle, so as to rotate the trip bar 40. The plates 42 and 43 are arranged at right angles with respect to each other. The trip rod 40 is rotatably supported by bearings 44, and a crank 45 is secured to each end of the trip bar 40. A pin 46 pivotally connects each of the cranks 45 to a link 47, and a pin 48 pivotally connects each of the links 47 to the complementary shift rod 37. Thus, rotation of the trip bar 40, which is caused by the wheels of the vehicle engaging one of the plates 42 or 43, results in the rod 37 being shifted, thereby opening and closing the gates 21 as later described in this application. A suitable recess 49 is arranged in the ground adjacent each end of the shift rods 37 so as to provide sufficient clearance or room for the links 47 and cranks 45 to move in.

The other trip bar 41 is also provided with a pair of plates 50 and 51 which are arranged at right angles with respect to each other and the plates 50 and 51 are adapted to be engaged by one of the wheels of a vehicle for rotating the trip bar 41. The trip bar 41 is also provided with the cranks 45 which are pivotally connected to the links 47, the links 47 being pivotally connected to the shift rods 37, as previously described.

A lock is provided for selectively maintaining the pair of gates 21 in their closed position, as shown in Figure 1, whereby accidental opening or swinging movement of the gates 21 will be prevented. The lock is designated generally by the numeral 52, and is interposed between the pair of vertically-disposed standards 23. The lock 52 includes a bracket 53 that comprises a vertically-disposed leg 54 and a horizontally-disposed leg 55. The horizontally-disposed leg 55 is anchored to a concrete block 56 which may be embedded in the ground by suitable bolt-and-nut assemblies 57, Figure 7. An arm 58 is pivotally connected to the horizontal leg 55 by a hinge 59, and the arm 58 and the leg 54 define therebetween a recess for receiving therein the plungers 27 so that the gates will not accidentally swing open. An inclined guideway 60 is secured to the upper end of the leg 54, the guideway 60 serving to guide the plungers 27, as when the gates are being swung to their closed position. Suitable bolt-and-nut assemblies 61 connect the arm 58 to the leg 54, the bolt 61 being slidably arranged in engagement with the arm 58 and leg 54. A suitable coil spring 62 is circumscribed on each of the bolts 61, whereby a shock absorber is provided to prevent the gates 21 from jarring and possibly damaging the lock 52, as when the gates are swung to their closed position.

There is also provided a mechanism for limiting outward swinging movement of the gates 21, and this mechanism also serves to maintain the gates in their open position, as shown in Figure 2, to allow the vehicle to pass between the gates 21. This mechanism is designated generally by the numeral 63 and includes a vertically-disposed post 64 which has its lower end secured in the ground G. A pair of inclined braces 66 are secured to opposite sides of the post 64, and the braces 66 are secured to and support an inclined

shelf 65. The shelf 65 has its upper end spaced from the post 64 so as to define a recess therebetween for receiving therein the spring-pressed plungers 27, whereby the gates will be held in open position until the plungers 27 are retracted into the vertical portion 22 of the gate 21. It will be seen that one of the mechanisms 63 is provided for each of the gates 21.

In use, the gates are normally closed, as shown in Figure 1. Then, when a vehicle, such as an automobile, is to pass through the gates 21, there is provided a means for automatically opening the gates without the necessity of having an occupant of the vehicle alight from the vehicle. Thus, if a vehicle is approaching the closed gates from the right of Figure 1, the vehicle is steered so that one of its wheels strikes or engages the plate 42 to thereby rotate the trip rods 40 in a counterclockwise direction. This rotation of the trip rod 40 causes the pair of cranks 45 on its end to swing in a counterclockwise direction, and since the cranks 45 are connected to the shift rods 37 by links 47, the shift rods 37 will be slid or moved to the position shown in Figures 2 and 4. This movement of the shift rods 37 in the bearings 38 and 39 causes tension to be applied to the cables 30.

As the cables 30 are pulled by the shift rods 37, the plungers 27 will first be upwardly retracted into the lower open ends of the vertical portions 22 of the gates 21. Thus, the plungers 27 will be lifted sufficiently so as to clear the upper ends of the legs 54. Then, continued movement of the shift rods 37 and the cables 30 causes the pair of gates 21 to be swung open to the position shown in Figures 2 and 4.

Outward swinging movement of the gates 21 is limited by the posts 64, since the gates will contact these posts. Also, when the gates 21 reach their open position, the springs 28 will urge the plunger 27 into the space between the shelf 65 and the posts 64 so that the gates will be retained or maintained in their open position. After the vehicle passes between the open gates 21, the vehicle is steered so that one of its wheels engages the plates 50 on the trip rods 41, thereby rotating the trip rod 41 in a counterclockwise direction. By means of the previously-described structure, this counterclockwise rotation of trip rod 41 will cause the shift rods 37 to move from the position of Figures 2 and 4 to the position shown in Figures 1 and 3. This latter movement of the shift rods 37 causes tension to be applied to cables 31, whereby the plungers 27 will initially be retracted out of engagement with the mechanism 63, and then the gates will swing to their closed position where they will automatically become locked. Similarly, a vehicle approaching from the opposite direction will serve to automatically open and close the gates 21 to permit passage therebetween of a vehicle without the necessity of having the occupants alight from the vehicle.

The gates can be opened by any vehicle, or even by means of a bicycle. Further, the device is inexpensive to construct and will open by a vehicle traveling at any reasonable speed.

What is claimed is:

1. In combination, a pair of spaced parallel vertically-disposed standards each having their lower ends supported in the ground, a gate pivotally supported by each of said standards and mounted for swinging movement about a vertical axis, each of said gates including a vertical tubular portion and a hollow horizontally-disposed portion secured to said vertical portion, a V-

shaped body member supported on each of said horizontally-disposed portions, a lock arranged intermediate said pair of standards, a spring-pressed plunger slidably arranged in the lower end of each of the vertical portions of each of said gates, said plunger being mounted for movement into and out of engagement with said lock for selectively maintaining said gates in closed position, a pair of cables connected to said body member and each having an end connected to said plungers, a pair of spaced parallel horizontally-disposed shift rods arranged on opposite sides of said standards, a pair of coil springs each having an end connected to each of said shift rods and their other ends connected to said cables, a pair of spaced parallel horizontally-disposed trip bars extending between the ends of said shift rods, a pair of plates arranged at right angles with respect to each other and secured to each of said trip bars and adapted to be engaged by a vehicle wheel, and means pivotally connecting said trip bars to said shift rods.

2. In combination, a pair of spaced parallel vertically-disposed standards each having their lower ends supported in the ground, a gate pivotally supported by each of said standards and mounted for swinging movement about a vertical axis, each of said gates including a vertical tubular portion and a hollow horizontally-disposed portion secured to said vertical portion, a V-shaped body member supported on each of said horizontally-disposed portions, a lock arranged intermediate said pair of standards, a spring-pressed plunger slidably arranged in the lower end of each vertical portion of each of said gates, said plungers being mounted for movement into and out of engagement with said lock for selectively maintaining said gates in closed position, a pair of cables connected to said body member and each having an end connected to said plungers, a pair of spaced parallel horizontally-disposed shift rods arranged on opposite sides of said standards, a pair of coil springs each having an end connected to each of said shift rods and their other end connected to said cables, a pair of spaced parallel horizontally-disposed trip bars extending between the ends of said shift rods, a

pair of plates arranged at right angles with respect to each other and secured to each of said trip bars and adapted to be engaged by a vehicle wheel, and means pivotally connecting said trip bars to said shift rods, said last-named means comprising a crank connected to each end of each of said trip bars, and a link pivotally connecting said cranks to the complementary ends of said shift rods.

3. The apparatus as described in claim 2, wherein said lock includes a bracket provided with a horizontally-disposed leg and a vertically-disposed leg, an inclined guideway secured to the upper end of the vertically-disposed leg of said bracket, an arm pivotally connected to the horizontally-disposed leg of said bracket and coacting with said vertically-disposed leg to define a recess for receiving therein the spring-pressed plungers, bolts extending between said arm and vertically disposed leg, and coil springs circumposed on said bolts.

4. The apparatus as described in claim 2, and further including a mechanism for limiting opening swinging movement of said gates and for coacting with said plungers to selectively maintain said gates in their open position, said mechanism embodying a vertically disposed post having its lower end secured in the ground, and a shelf coacting with said post to define a recess for receiving said spring pressed plungers.
